SHROUDED CAP FOR SPARKING PLUGS

Gustav Werner, Stuttgart, Germany, assignor to
 Robert Bosch Aktiengesellschaft, Stuttgart,
 Germany

Application November 9, 1931, Serial No. 573,977,
 and in Germany November 28, 1930

8 Claims. (Cl. 123—169)

The present invention relates to sparking-plugs and more particularly to shrouding caps for the same which are secured on the plug by means of a bow spring.

5 It has been found that in cases where the sparking-plug is difficult of access, the securing of the cap may be difficult, and the protective caps may often not correctly seat themselves when for instance the plug is not visible when the cap is to 10 be put in place.

According to this invention, a particularly simple construction, which during rough usage always remain firm and secure, is attained by a retaining spring which is held by a member bearing against the metallic cap and which can be tensioned.

An example of construction of the invention is illustrated in the accompanying drawing.

In the drawing, 1 is the sparking-plug, in which 20 the insulating body 4 carrying the central electrode 3 is secured by the nut 2. The protective cap 5 is placed over the part of the insulating body 4 which projects above the nut 2, and is seated on the latter. The cap has on its dome 25 an external lug or projection 6, which serves to hold a nut 7 in its position. Into this nut is screwed the screw-bolt 8, which is movably attached to the retaining spring 9. The two ends 30 of the spring are bent to form hooks 10, which are inserted in two conical openings 11 in a plate 12. The body of the sparking-plug 1 has a collar 13, which acts as an abutment for the plate.

This construction has the advantage that the 35 retaining spring can be put on in an untensioned condition without using any force and then tightened up. By this means the use of strong springs, which, without the tensioning device, could only be put on with the aid of a tool is made possible.

40 I declare that what I claim is:

1. A shrouded cap for sparking-plugs comprising in combination a hollow cap, a bow spring, means to engage the free ends of said spring with an abutment on the plug and telescopic tensioning means between said bow and said cap.

2. A shrouded cap for sparking-plugs comprising in combination a hollow cap, an abutment on said cap, a bow spring, expansion nut and bolt 50 means threaded on said bow spring and means to engage the free ends of the said bow spring with an abutment on the plug.

3. A shrouded cap for sparking-plugs comprising in combination a hollow cap, an abutment 55 on said cap, a bow spring, expansion nut and bolt

means threaded on said bow spring and engaging the abutment on the cap, a ring engaging behind a flange on the plug and engaged by the free ends of said bow spring.

4. As an article of manufacture a tensioning 60 spring for the caps of sparking-plugs comprising a bow, hooked ends on the bow, and an expansion nut and bolt threaded on the bow.

5. A shrouded cap for sparking plugs comprising in combination a hollow cap, a spring member engaging an abutment on the plug and extending over said cap and a tension device between said spring member and said cap for adjusting the tension of said spring member and transmitting the tension thereof to said cap. 70

6. The combination with a spark plug having a circumferential projection intermediate its outer terminal and the portion of the plug engaging the engine cylinder, of a cap extending over the outer terminal of the plug and freely engaging the plug body, a ring member rotatably engaging about the body of the plug beneath and against the circumferential projection thereon, a bow spring having its ends secured in said ring member and extending in spaced relation over the top of said cap, and a tensioning device between said bow spring and the top of said cap. 80

7. The combination as set forth in claim 6 and in which said tensioning device comprises nut-and-bolt means threaded on said bow spring and engaging the top of said cap. 85

8. The combination as set forth in claim 6 and in which said tensioning device comprises a threaded nut mounted in fixed angular position 90 on the top of said cap and a bolt secured to said bow spring and engaging said nut.

GUSTAV WERNER.
